UNITED STATES PATENT OFFICE.

AUGUST FISCHER, OF WINCHESTER, ASSIGNOR OF ONE-HALF TO JAMES F. POTTS, OF WHITEHALL, ILLINOIS.

STEM WINDING AND SETTING WATCH.

SPECIFICATION forming part of Letters Patent No. 400,202, dated March 26, 1889.

Application filed November 5, 1888. Serial No. 290,068. (No model.)

to all whom it may concern:

Be it known that I, AUGUST FISCHER, a citizen of the United States, residing at Winchester, in the county of Scott and State of Illinois, have invented certain new and useful improvements in Stem Winding and Setting Watches, of which the following is a description.

This invention relates to stem-winding watches.

The invention consists in the construction and combination of parts by which the winding-bar is retained in its various operative positions.

Figure 1 is a section and partial elevation of part of the outer rim of a watch, showing gravity-catch in proximity to the winding-bar, the winding-bar being in its inner position. Fig. 2 is a similar view with winding-bar in its outer position. Figs. 3 and 4 are similar views showing gravity-catch at one side only of winding-bar. Fig. 5 is a face view of gravity-catch, Fig. 1, and Fig. 6 an elevation of winding-bar with head in section.

25 A indicates the outer rim of a watch-case. This rim has a recess near the pendant D for the reception of a gravity-catch, B. The pendant and rim have the usual passage for the winding bar or pin C. Pins or stops A' A' in the rim limit the movement of the gravity-catch B. The bar or pin C carries gears F G, one of which engages a winding-gear, II, when the bar C is in its outer position, the other engaging the setting-wheel I when the pin is 30 pressed inward, at the same time disengaging the winding-gear, as is common in winding mechanism of this class. The bar or pin C has a milled head, C', and a spring, S, in a recess in the pendant bears against this head to 35 push it outward. The pin or bar C has one or more grooves, C², or other inequalities with which the gravity-catch B may engage in certain positions.

The gravity-catch B is preferably a thin 45 plate of metal, curved lengthwise to conform to the recess in the rim, and having the sides rounded to form bearing-surfaces. The catch

preferably has a perforation, B', shaped like a key-hole, through which the pin or bar C passes, as shown in Figs. 1 and 2. With this 50 construction the normal position of the bar C is shown in Fig. 1, the bar or pin C passing through the small end of the key-hole slot. In this position the watch may be turned over; but the catch B will be held from sliding by 55 the bar C. The watch is then in position for winding.

For setting the hands, the bar C is pressed inward and the watch turned in such position that the gravity-catch B will slide downward, 60 the narrow slot of the passage B' then embracing the grooved part C² of bar C. Then on releasing the pressure from the button C' of pin C said pin will be held by the catch B from any longitudinal movement, but may be 65 turned to operate the setting-gear. By holding in the pin and turning the watch over the pin may be released.

Fig. 4 shows a gravity-slide which engages the groove at only one side of the winding-bar. 70 Fig. 3 shows still another form of gravity-catch. It is apparent there may be many forms.

I claim—

1. The combination, with the sliding winding-bar of a stem-winding watch, of a gravity-catch in the case in position to engage and hold said bar against longitudinal movement, 75 substantially as described.

2. The combination, with the winding-bar of a stem-winding watch and a spring bearing 80 the same outward, of a sliding gravity-catch in the casing, and stops to limit the movement of said catch, substantially as stated.

3. The combination, with the grooved winding-bar of a stem-winding watch, of a sliding 85 gravity-catch having a perforation through which said bar passes, said perforation being of unequal width, so as to embrace and hold the grooved portion of the bar when in one position, as set forth.

AUGUST FISCHER.

HENRY S. AVERY.

Corrections in Letters Patent No. 400,202.

It is hereby certified that in Letters Patent No. 400,202, granted March 26, 1889, upon the application of August Fischer, of Winchester, Illinois, for an improvement in "Stem Winding and Setting Watches," errors appear in the printed specification requiring correction, as follows: In line 52, the word and figure "Fig. 1" should read *Fig. 2*, and in line 53 the word "small" should read *large*; and the said Letters Patent should be read with these corrections therein that the same may conform to the record of the case in the Patent Office.

Signed, countersigned, and sealed this 30th day of April, A. D. 1889.

[SEAL.]

CYRUS BUSSEY,
Assistant Secretary of the Interior.

Countersigned:

C. E. MITCHELL,
Commissioner of Patents.
